Inventor:
Howard C. Marks.

UNITED STATES PATENT OFFICE

128,670

DESIGN FOR A RETAINER PLATE FOR OIL FILTERS

Howard C. Marks, Alexandria, Nebr.

Application March 13, 1941, Serial No. 99,564

Term of patent 14 years

To all whom it may concern:

Be it known that I, Howard C. Marks, a citizen of the United States of America, residing at Alexandria, in the county of Thayer and State of Nebraska, have invented a new, original and ornamental Design for a Retainer Plate for Oil Filters, of which the following is a specification, reference being had to the drawing which accompanied my original application wherein:

Figure 1 is a top perspective view of a retainer plate for oil filters; and

Figure 2 is a bottom perspective view thereof showing my new design.

I claim:

The ornamental design for a retainer plate for oil filters, as shown.

HOWARD C. MARKS.
